ATTACHMENT FOR FLOOR SANDERS
OR THE LIKE

Francis C. Cooke, Hartford, Conn.

Application February 5, 1947, Serial No. 726,556

1 Claim. (Cl. 51—177)

1

This invention relates to an attachment for floor-sanding machines, and more particularly to an attachment which will enable the sanding of floors to be effected under radiators or articles of furniture and in other locations which cannot be reached with the usual machine.

When floors are refinished, this, of course, is ordinarily done with a so-called "sanding machine," usually electrically driven. In addition to the machines for sanding the main portion of the floor, so-called "edgers" are provided which enable the sanding of areas close to the walls or baseboards of the room which cannot be done with the larger machines, and this saves the hand scraping of such areas. However, even with such machines, it is not possible to scrape any portion of the floor which is not accessible from above, and, therefore, such portions as may be under radiators or articles of furniture which may be permanent or difficult to move cannot be reached.

I contemplate by the present invention the provision of an attachment which may be readily and easily applied to existing machines, the attachment being adapted to project laterally from the body of the machine and being of very low height, so that it can extend below a radiator or any article of furniture which may be spaced even a short distance above the floor level. Moreover, the sanding disk is positioned at the extreme end of the attachment, so that the floor may be scraped substantially flush with the wall or baseboard, and a clean job accomplished.

One object of the invention is to provide an attachment for floor sanders which will enable the scraping of floors below articles of furniture.

A further object of the invention is to provide a floor sander comprising a laterally extending arm or support which carries a sanding disk, this support being of low height and projecting laterally from the main frame of the sander, whereby it may extend under articles of furniture.

A still further object of the invention is to provide an attachment which may be readily and easily connected to a sanding machine, the attachment extending laterally from the body of the machine and carrying a rotating sanding disk and driving connections between this disk and the drive of the sanding machine.

To these and other ends the invention consists in the novel features and combinations of parts to be hereinafter described and claimed.

In the accompanying drawings:

Fig. 1 is a side elevational view of a floor-sand-

2

ing machine having my attachment applied thereto;

Figs. 2, 3 and 4 are fragmentary elevational views of the lower portion of the machine, showing the manner of securing the attachment to the case;

Fig. 5 is a top plan view of the attachment removed from the machine;

Fig. 6 is a sectional view on line 6—6 of Fig. 5;

Fig. 7 is a bottom plan view of the attachment; Fig. 8 is a sectional view on line 8—8 of Fig. 6; and

Fig. 9 is a sectional view through the drive pulley.

To illustrate a preferred embodiment of my invention, I have shown a floor-sanding machine having a housing 10, the longitudinal dimension of which is generally vertically disposed. To this housing is secured a lower housing 11 in which is mounted the sanding disk 12 (Fig. 6), which is adapted to carry the sheet of sandpaper or other abrasive material in a well-known manner. The disk 12 is secured to the lower end of a shaft 13, this shaft being rotatably mounted in the housing and suitably driven so as to rotate the disk 12 to sand or scrape the floor. It may be noted that the portion 11 of the housing is open at the bottom to permit the abrasive sheet mounted upon the disk 12 to contact the floor.

As shown in Fig. 4, the lower housing portion 11 is provided with a laterally projecting ear 14, and, as will be explained hereinafter, this ear is employed to secure the attachment in place. Likewise, lugs 15 are provided upon the housing 10 to receive bolts 16 to secure the two portions of the housing together, and under the head of one of these bolts may be secured a hook-shaped member 17, which may also be employed to secure the attachment in place, as will be more fully described later.

As shown more especially in Figs. 5 to 8 of the drawings, the attachment comprises a supporting casing 20, this casing being hollow and provided with upper and lower walls 21 and 22. In the upper wall is provided a relatively large upwardly facing opening 23 which communicates with the downwardly facing opening in the housing 11 through which the disk 12 projects. The lower wall 22 of the casing 20 is provided with a downwardly facing opening 24 through which projects a sanding disk 25 carried by a hub 26 rotatably mounted in the casing, this hub being provided with a belt or pulley groove 27. A sheet of sandpaper or other abrasive 28 is secured to the disk

25 by means of a screw 41, to be described hereinafter.

It has already been stated that the disk 12 carried by the vertical shaft 13 of the sander is adapted to support an abrasive disk upon its lower face. This sheet of abrasive material is adapted to be secured in place by a screw threaded into the shaft 13 which is provided with a threaded opening 30 for this purpose.

For applying my attachment to the machine, I provide a pulley 31 having a threaded screw 32 secured thereto which may be threadingly received in the opening 30 when the screw which normally holds the abrasive sheet in place has been removed, so that the pulley 31 may then be rigidly secured to the shaft 13 below the disk 12. A belt 34 is trained around the pulley 31 and the grooved hub 26 of the disk 25, whereby, when the shaft 13 is rotated, the disk 25 will likewise be rotated. It will, therefore, be noted that the driving mechanism which normally drives the disk 12 of the sanding machine will be employed to drive the sanding disk 25 of my attachment, and, if the pulleys 31 and 26 are of substantially the same diameter, the disk 25 will be rotated at the same speed as would usually be imparted to the disk 12.

My attachment is applied to the lower face of the housing portion 11, the latter being adapted to rest upon the rear portion of the casing 20 or that portion surrounding the opening 23. In order that the attachment may be readily secured in place without the use of tools, I provide the attaching devices shown in Figs. 1 to 4.

To this end, a bail or looped member 36 is pivoted at 37 to a lug 38 upon the case 20, and pivoted to the upper end of this loop member is a metal strip or plate 39, the depending free end of which may be engaged in the hook 40 of the member 17. It will be seen that, after engaging this end of the member 39 in the hook 40, the upper end of the loop 36 may be moved toward the casing or to the left, as shown in Fig. 3, and thus move the arms of the loop 36 past dead center position, as shown in this figure, so as to secure the casing 20 to the housing 11. In the position of the parts shown in Fig. 3, the tension upon the loop 36 would tend to move this loop toward the casing instead of moving it toward the right, or away from the casing, as would be necessary to disconnect the parts. I have found that this is a very convenient and satisfactory manner of securing the parts together, so that the attachment may be readily attached or detached without the use of tools.

Similarly, another loop or hasp member 41 is pivoted to the casing 20 at 42, and to the upper end of this loop is also pivoted a metal strip or plate 43, which is designed to engage the upper surface of the lug 14 rearwardly of the bolt 44, and the loop 41 may also be moved against the housing 11 past dead center position so as to secure the casing in place at the side of the housing opposite the loop 36.

As shown more especially in Figs. 1 and 7, casters 45 are provided upon the lower surface of the casing 20, these casters being below that portion of the casing which supports the housing 10, so that the weight of the sanding machine will be carried upon these casters. At its forward end, the casing 20 is adapted to be supported from the floor by the sanding disk 25, so that the latter will be in contact with the floor.

In Fig. 8 of the drawings, I have shown in detail the manner of securing the pulley hub 26 in

place. This hub is threaded upon the screw 47 which will preferably be provided with left-hand threads so that the rotation of the disk will not tend to loosen it from the screw. This screw 47 is carried by the inner race 48 of a ball bearing, the outer race 49 of which is received snugly in an opening 50 of the upper wall 21 of the casing 20. This outer race 49 of the ball bearing may be held against removal by screws 51, the heads of which underlie the edges of the race 49, and these screws 51 may be inserted through openings 52 in the pulley hub 26.

In assembling the parts, the screw 47 is placed within the ball bearing before the latter is inserted into the opening 50, and this screw may be held against rotation by a screwdriver or the like applied to the slot 53 in its upper end, while the hub 26 is screwed firmly thereon. The ball bearing may then be placed in the opening 50 and the screws 51 inserted through the openings 52 to hold the bearing in place.

Thereafter, the abrasive sheet 28 may be placed upon the disk 25 and secured thereto by the nut 54 threaded upon the lower reduced end 55 of the screw 47. This portion of the screw will preferably carry the usual right-hand thread. If desired, a disk of cushioning material 56 may be placed between the disk 25 and the abrasive sheet 28, and it will be noted that the pulley hub 26 is slightly countersunk, so that the nut 54, when screwed in place, will lie above the surface of the abrasive sheet 28 in order that the latter may properly contact the floor and the nut be held out of engagement with the floor.

It will be apparent that in attaching my device to a floor sander, it is only necessary to remove from the opening 30 of the shaft 13 the usual screw which holds the abrasive disk and insert in its place the screw 32 of the pulley 31. The attachment can then be secured in place by means of the loops 41 and 36, and the device is ready for use.

It will be also appreciated that, as the casing 21 extends laterally from the housing portions 10 and 11, and is of very low height, it will enable the sanding of floor areas which cannot be reached with the usual machine. Moreover, as the sanding disk 25 is positioned at the extreme outer end of the attachment, floor areas adjacent walls or baseboards or other obstructions on the floor may be reached without leaving an unsanded area adjacent thereto.

At the upper portion of the casing 20, and adjacent the opening 23, are provided supporting platforms 23^a to which the casters 45 are secured. It will also be noted that the lower wall 22 of the casing is removable and secured in place by screws 22^a, as shown in Fig. 7, in order that access may be had to the belt 34 and pulley 31.

As shown in Fig. 9 of the drawings, the pulley 31 is preferably made in two sections 60 and 61, respectively, which sections are detachably held together by screws 62. Between the sections may be placed one or more shims 63. By removing the screw 62 and increasing or decreasing the number of shims, the pulley grooves may be adjusted in width to adjust the tension upon the belt 34. It will be obvious that, when the two sections 60 and 61 of the pulley are brought closer together, the belt will be tightened.

While I have shown and described a preferred embodiment of my invention, it will be understood that it is not to be limited to all of the details shown, but is capable of modification and

variation within the spirit of the invention and within the scope of the claim.

What I claim is:

An attachment for floor-sanding machines having a housing provided with a downwardly-facing opening and a rotating sanding disk projecting through said opening for contact with the floor, said attachment comprising a hollow casing having an upwardly-directed opening adjacent its rear end and a downwardly-directed opening adjacent its front end, means for attaching the casing to the housing of the sanding machine to support the latter from the floor with the upwardly-directed opening of the casing registering with the downwardly-directed opening of the housing to receive the sanding disk in the latter whereby the sanding machine is supported from the floor upon the portion of the casing about said opening, a second sanding disk rotatably mounted in the casing on a substantially vertical axis and projecting downwardly through the front opening of the casing, means drivingly connecting said sanding disks including a pulley

adapted to be secured to each of said disks and a belt connecting said pulleys and extending through said hollow casing, said casing being closed except for said opening and its interior providing a passage for the belt and abraded material, supporting platforms provided on said casing adjacent and at the rear of said upwardly-directed opening, and floor-engaging casters secured to the underside of said platforms.
